LEO GREENBAUM, OF FAR ROCKAWAY, EDWARD VAN HOOFSTADT, OF OCEANSIDE, AND CHARLES GUSTAVSON, OF BROOKLYN, NEW YORK, ASSIGNEES TO LION MATCH COMPANY, INC., A CORPORATION OF NEW YORK.

FEEDING AND CUTTING PAPER MATCH SPLINTS.

Application filed April 30, 1925, Serial No. 27,111. Renewed July 23, 1927.

Our invention relates to improvements in machines for making book matches or matches such as are usually made of paper and wire stitched in a paper cover. More particularly, the invention has reference to means in such a machine for feeding, cutting, and placing in position rows of match splints preferably in several layers to be secured in a match cover.

In the accompanying drawing, we have illustrated a section of such a machine embodying an application of our invention.

Referring thereto, 5 indicates a suitable source of power such as an electric motor 15 having a pinion 6 meshing with the pinion 7 upon the shaft 8 mounted in the bearing 9, said shaft also having a pinion 10 meshing with the pinion 11 loosely mounted upon the main shaft 12 and being provided with a drum 13.

14 indicates a suitable clutch mechanism pivotally connected by the bar 15 to the rocker 16 pivoted upon the support 17 and pivotally connected to the bar 18 which in turn is pivotally connected to the bar 19 pivotally supported at 20, a handle 21 being provided, so that when the handle 21 is operated, the cone 22 of the clutch is shifted between the fingers 23 which in turn drive the disc 24 against the disc 25, overcoming the spring 26, thereby causing the drum 13 to frictionally engage the disc 27 pivoted to the shaft 12 at 28 as shown.

29 indicates an endless belt or other suitable conveyor mechanism having spacing blocks 30 which move leftwardly beneath the tray 31 passing through the tunnel or passage 32. Upon the tray or chute 31 slotted cards or match combs 32' are placed preferably double, that is to say, two, one upon the other, preferably by hand, the matches in the combs being preferably separated by the removal of every tenth or eleventh match, as indicated at 33.

Upon said drive shaft 12 is provided a cam 34 upon which rides the roller 35 in the end of the rocking lever 36 pivoted at 37 and at the opposite end pivoted to the link 38 which in turn is pivoted to the reciprocating carriage 39 upon the bearing 40 and which carries a bracket 41 which is provided with pins 42 and 43 upon each of which is pivot-

ally mounted fingers 44 and 45 respectively, gravity serving to keep said fingers upon the cards 32' upon the tray 31, so that the said carriage 39 reciprocates laterally such distance as to have the fingers drop into the spaces 33, thereby feeding successively and intermittently a card or cards of ten or eleven matches each. 46 indicates a light spring which bears upon the tops of the matches to keep them flat in position upon the tray 31.

As the covers 47 for the matches are fed leftwardly beneath the tray 31, as more particularly set forth in a copending application Serial No. 660,781, filed September 4, 1923, or application Serial No. 27,110, filed April 30, 1925, the knife 48 cuts the matches from the card at the point of separation such as 33. This knife 48 is secured to the vertically reciprocating block 49 in the frame 50 and is pivotally connected to the lever 51, the outer end of which is pivotally connected to the link 52, the lower end of which is provided with a roller 53 which rides in the cam 54 upon the shaft 12. 54' is another rod provided with a roller 55, adapted to ride upon the cam 56, against the action of the spring 57, and causes the presser-foot 58 to vertically reciprocate in the guide 59. It will be noted from the drawing that the cam 54 is advanced with respect to the cam 56 on the shaft 12 and it therefore follows that the knife 48 operates slightly in advance of the pressure foot 58. Accordingly, when the knife 48 severs a portion of the match strip, the downward movement of the knife to effect the severing operation will be followed by a similar movement of the presser foot 58 which will operate in a slightly retarded relation to the knife, so that as soon as a portion of the card is severed the presser foot will immediately engage the card and force it downwardly upon the subjacent cover portion. It therefore follows that the severed match card is positively depressed by the presser foot and is not dependent for its positioning operation upon gravity. After the card has been positioned on the cover in the manner described, the cover and its associated card are adapted to be fed leftwardly through the machine together and beneath the light spring 60 into the forming tunnel

or passage 32 while the covers are folded over the matches and the same are stitched together.

Of course it will be understood that various modifications may be made in the construction and arrangement of parts without departing from the spirit of the invention as claimed.

We claim:—

10. 1. In a match strip feeding mechanism for match book machines, having a cutter operable to sever successive match cards from the strips, a weighted feeder reciprocable toward and from the cutter and operative in its movement toward the cutter to engage a strip between the splints thereof and feed it to the cutter, and adapted when moved from the cutter to slide freely over the strip without engaging the same, said feeder having a substantially flat smooth base and depending finger, said base being adapted to rest upon the splints and said finger adapted to engage therebetween.
15. 2. In a match strip feeding mechanism for match book machines having a cutter operable to sever successive match cards from the strips, the combination of a stationary feed table positioned in advance of the cutter and on which match strips are adapted to be supported to be fed to the cutter, a carrier mounted for rectilinear reciprocating movement toward and away from the cutter and in advance thereof, and a plurality of pusher fingers pivotally mounted in tandem on the carrier and impelled at all times toward the stationary table, said pusher fingers being shaped to engage with transversely extending edges of the strips on the table and operable during movement toward the cutter to engage such edges of said strips to feed the strips successively to the cutter and adapted, when moved from the cutter, to slide freely over the strips, and means for reciprocating the carrier.
20. 3. In a match strip feeding mechanism for match book machines having a cutter operable to sever successive match cards from the strips, the combination of a carrier mounted for rectilinear reciprocating movement toward and away from the cutter and in advance thereof, and a plurality of weighted

pusher fingers pivotally mounted in tandem on the carrier and gravitating at all times into the path of the strips to the cutter, said pusher fingers having blunt noses adapted for engagement with transversely extending edges of the strips, and operable during movement toward the cutter to engage such edges of said strips to feed the strips successively to the cutter and adapted when moved from the cutter to slide freely over the strips, and means for reciprocating said carrier.

4. In a match strip feeding mechanism for match book machines having a cutter operable to sever successive match cards from the strips, the combination of a carrier mounted for rectilinear reciprocating movement toward and away from the cutter and in advance thereof, and a plurality of pusher fingers pivotally mounted on the carrier in tandem and impelled at all times into the path of the strips to the cutter, said pusher fingers having blunt noses adapted for engagement with transversely extending edges of the strips, and operable during movement toward the cutter to engage such edges of said strips to feed the strips successively to the cutter and adapted when moved from the cutter to slide freely over the strips, and means for reciprocating said carrier.

5. In a match strip feeding mechanism for match book machines having a cutter operable to sever successive match cards from a strip, a stationary feed table in advance of the cutter and on which match strips are adapted to be supported to be fed to the cutter, a feeder reciprocable toward and away from the cutter and provided with a plurality of strip engaging elements arranged in tandem and maintained in engagement with a match strip on the stationary table, and means to reciprocate said feeder, said match engaging elements being shaped to engage with the splints of the comb strip when the feeder is moved toward the cutter to feed the strip to the cutter and to slide idly over the strip without imparting movement thereto when the feeder is moved in a direction away from the cutter.
